Filed Jan. 17, 1963, Ser. No. 73,219

Term of patent 14 years

(Cl. D86—10)

Fig. 2

FIG. 1 is an isometric view of an applicator for shaving foam or the like, showing my new design; and

FIG. 2 is an isometric view taken from the lower side of FIG. 1.

The characteristic features of my design reside in an applicator of the configuration shown having a curved application blade like portion ending with an oblong base having a finger receiving opening therein, all as shown.

I claim:

The ornamental design for an applicator for shaving foam or the like, as shown and described.
